HYDROCARBON-MOTOR.

1,163,935.

Specification of Letters Patent. Patented Dec. 14, 1915.

Application filed March 22, 1903. Serial No. 485,077.

To all whom it may concern:

Be it known that I, ALLEN LOOMIS, a citizen of the United States, residing at Detroit, in the county of Wayne and State of Michigan, have invented certain new and useful Improvements in Hydrocarbon-Motors, of which the following is a specification.

This invention relates to motors and particularly to hydrocarbon motors of the type employing sliding valves. In the particular embodiment shown in the drawings, it is applied to a motor having sleeve valves arranged to reciprocate between the piston and the cylinder walls, for the purpose of closing and opening the inlet and exhaust ports of the motor by cooperating openings or ports in the valves.

While the invention was especially designed for use on the particular form of motor shown and has peculiar advantages when so applied, it will be understood that its broad features are applicable to other forms.

One of the principal objects of the invention is to operate the valves of the several cylinders of a multi-cylinder motor by means which will be simple in construction and effective. In other words to reduce as far as possible the number of working parts necessary to effect the various operations.

Other objects and advantages will appear from the following description taken with the accompanying drawings in which.—

Figure 1 is a longitudinal section and part elevation of a four-cylinder motor embodying some of the features of my invention; Fig. 2 is a cross section approximately on the line 2—2 of Fig. 1; Fig. 3 is a fragmentary view similar to Fig. 2 with the moving parts in different relative positions; Fig. 4 is a detail sectional view of a portion of the cylinder head shown in Fig. 2; Fig. 5 is a plan view and part section illustrating another form of valve reciprocating means; Fig. 6 is a fragmentary cross section on the line 6—6 of Fig. 5; Fig. 7 is a view partly broken away of another form of valve reciprocating means, and Fig. 8 is a longitudinal section and part elevation of a four-

cylinder motor embodying the valve reciprocating means shown in Fig. 7.

1, 2, 3 and 4 represent respectively the four cylinders of the multi-cylinder motor shown in Fig. 1, and 5 represents the crank shaft turning in the bearings 7 in the crank case 6. As shown particularly in Fig. 2 this crank case is preferably made in three parts, viz., the upper part or supporting frame 8, the intermediate section 9 between which and the support 8 the bearings 7 are contained, and the bottom cover or oil well section 10 which latter section is easily removable to give access to the interior of the crank case. The cranks 11 of the crank shaft 5 are set 180° apart and the connections are so made that the order of firing when the motor is operated on the four-stroke cycle, is successively in cylinders 1—2—4—3.

The fly wheel is shown at 12 mounted on crank shaft 5. In each of the cylinders is arranged the usual piston 13 connected to its respective crank by the connecting rod 14. Each cylinder is provided with suitable inlet ports 15 and opposite outlet or exhaust ports 16, these ports having suitable pipe connections with the carburetor and exhaust pipe respectively. Each cylinder also has a removable head 17, the central portion of which extends down into the cylinder coaxially with the piston, leaving an annular space between its periphery and the cylinder walls above the inlet and exhaust ports. The cylinders and their heads are suitably water-jacketed as shown at 18.

It will be noted that the water chamber in that part of the head which extends into the cylinder is lower than its water outlet 19 and therefore it is impossible to properly drain this water chamber. This water however, should be removed when the motor is standing idle, particularly in cold weather when it would be likely to freeze and to accomplish this an opening 20 is provided in the head over the deepest part of the chamber, and a suction pump 21 is inserted for withdrawing the water. (See Fig. 4.) It will be understood that the opening 20 is

normally closed by a removable plug 22. This means for removing the trapped water in the cylinder head is an important feature of this invention, since without some such means it is hardly a commercial possibility to manufacture and ship motors of this character in a cold climate. The motors, particularly if employed on motor vehicles, must be tried out before they are shipped which of course necessitates filling the water jackets, and after such trial, if it were necessary to remove the cylinder heads for the purpose of draining them, the last trying out of the motor would have lost much of its value for the reason that the heads might be improperly placed on the motor after being drained and the liability of shipping a motor in imperfect condition would be thereby greatly increased.

Arranged to reciprocate longitudinally in each cylinder are two concentric sleeves which surround the piston and the downwardly extending central portion of the head above described, the inner sleeve forming the piston barrel and both sleeves having ports arranged to cooperate to open the inlet and exhaust ports of the cylinder. The inner sleeve 23 has the oppositely arranged ports 24-25 which during the movement of the sleeve register respectively with the ports 15 and 16, and the outer sleeve 26 has the ports 27 and 28 which also register at times with the ports 15 and 16 respectively. From this it will be observed that in order to open communication between the inlet port 15 and the interior of the cylinder it is necessary that the ports 24 and 27 shall simultaneously register with the inlet port 15, and in order to open communication between the interior of the cylinder and the exhaust port 16 it is necessary that the ports 25 and 28 shall simultaneously register with said exhaust port 16. It will also be observed upon reference to the drawings that the above mentioned ports are so arranged and the sleeves so reciprocated that the inlet port 15 is open to the interior of the cylinder during every other down stroke of the piston, or one opening for every two complete revolutions of the crank shaft, and the same is true of the exhaust port 16 except that it is opened on the up stroke of the piston which succeeds the firing down stroke thereof. The mechanism for thus reciprocating the sleeves will now be described.

Mounted preferably in the upper or supporting section 8 of the crank case is a valve operating shaft 29, shown in Fig. 1 as turning in the bearings 30. This shaft may be rotated by the crank shaft at half the speed of said crank shaft by any suitable gearing which gives it one revolution for every two revolutions of the crank shaft. In the present instance this gearing includes the

sprocket 31 on the shaft 29 and the sprocket 32 on the crank shaft, the former sprocket having twice as many teeth as the latter, and a chain 33 operatively connects the sprockets. A forward extension 34 on the supporting section of the crank case forms a housing for the sprockets and chain, and the front end of this housing is closed by a removable cover 35 as will be clearly understood.

As heretofore constructed, motors of this type having sliding valves for controlling the inlet and exhaust ports have had a separate actuator such as an eccentric for moving each of said valves. Heretofore also it has been the practice in multi-cylinder motors of this type to disregard the relative positions of the sleeves or sliding valves of the various cylinders, and no attempt has been made to operate a sleeve or sliding valve of one cylinder in coincidence or in phase with the sleeve or sliding valve of another cylinder. In the present invention, however, these matters have been carefully worked out and the ports in the valve sleeves have been so arranged with relation to the ports in the cylinder and to the head 17 that the inner sleeve of each cylinder will be at all times a quarter period ahead of the outer sleeve of the same cylinder and also a quarter period ahead of its corresponding sleeve of the cylinder which fires next. Of course it is necessary that the sleeves of each cylinder shall be a quarter period ahead of their corresponding sleeves in the next firing cylinder so long as the cranks of the crank shaft are arranged 180° apart, but the degree of difference between the sleeves of the same cylinder and the positions of the ports in the sleeves are matters which may be varied within wide limits and with various results as regards ease of manufacture and the time of opening and closing the inlet and exhaust ports. Various means may be used for actuating the sleeves and where eccentrics are employed for that purpose they will of course be arranged 90° apart so as to secure the operation of the sleeves a quarter period apart as above described. In the four-cylinder motor shown therefore there will be only four positions for the eight eccentrics, thus bringing two eccentrics in line on the shaft and permitting them to be machined and ground in pairs instead of separately.

Aside from the manufacturing advantages of arranging the sleeves at a quarter period apart, it is found that some of the eccentrics which would otherwise be necessary may be entirely dispensed with and that six, four, or even one eccentric may be made to actuate all of the sleeves. The method of actuating the eight sleeves from six eccentrics is illustrated in Figs. 1 and 2

of the drawings and by referring thereto it will be seen that the eccentric 36 reciprocates the inner sleeve 23 of cylinder No. 1 through the connecting rod 37 which extends between said eccentric 36 and the ears 38 on the enlarged lower end 39 of said sleeve 23, the pin 40 passing through the upper end of said connecting rod 37 and the ears 38 as will be readily understood. The eccentric 41 reciprocates the outer sleeve 26 of cylinder No. 1 and the inner sleeve 23 of cylinder No. 2 through the connecting rod 37. The eccentric 42 reciprocates the outer sleeve 26 of cylinder No. 2 through its connecting rod 37. Thus the four sleeves of cylinders 1 and 2 are actuated by the three eccentrics 36, 41 and 42, this being rendered possible by the fact that the outer sleeve 26 of cylinder No. 1 and the inner sleeve 23 of cylinder No. 2 move coincidentally. Also it will be noticed that the ears 38 on the outer sleeves of cylinders 1 and 2 are dropped down slightly below the lower edge of the sleeves, and this is necessary in the case of the outer sleeve of cylinder No. 1 to provide for its connection with the connecting rod 37 by the same pin 40 that connects said rod with the inner sleeve 23 of cylinder No. 2. In the case of cylinder No. 2 it is desirable since it makes it possible to have all of the connecting rods 37 of the same length, which of course is a distinct advantage in manufacturing.

The arrangement of the eccentrics and sleeves of cylinders 3 and 4 is identical with that of cylinders 1 and 2 except that the parts are shown in opposite phase with cylinder No. 4 leading. Thus the outer sleeve 26 of cylinder No. 3 is reciprocated through its connecting rod 37 by the eccentric 43; the inner sleeve of cylinder No. 3 and the outer sleeve of cylinder No. 4 operate coincidentally and are reciprocated through connecting rod 37 by the eccentric 44, and the inner sleeve of cylinder No. 4 is reciprocated through its connecting rod 37 by the eccentric 45. The first, third, fourth and sixth connecting rods 37 are shown in their extreme up or down position and the second and fifth rods are in intermediate position, while the arrows on them indicate the direction in which they are traveling.

Since the inner sleeve 23 of cylinder No. 1 and the outer sleeve 26 of cylinder No. 3 move coincidentally, one of the eccentrics 36 and 43 may be dispensed with and the two sleeves connected so that one will actuate the other, or the two sleeves may be actuated by a single means, as through the rock shaft 58 illustrated in Figs. 5 and 6. Referring particularly to said figures, the eccentric 36 is shown with its connecting rod 37 broken away near the top and it will be understood that this connecting rod is connected

through the pin 40 with the ear 38 on the inner sleeve 23 of cylinder No. 1. The opposite end of the pin 40 works in the slide blocks 51 in the forked arm 52 which is keyed to the rock shaft 53. Thus the reciprocating movement of the sleeve 23 of cylinder No. 1 imparts an oscillatory movement to the rock shaft 53, and said rock shaft in turn imparts a like reciprocating movement to the outer sleeve 26 of cylinder No. 3 through the forked arm 54 and sliding blocks and pin as illustrated in connection with the arm 52. Thus the single eccentric 36 reciprocates coincidentally both the inner sleeve of cylinder No. 1 and the outer sleeve of cylinder No. 3, and it will be readily understood that the outer sleeve of cylinder No. 2 and the inner sleeve of cylinder No. 4, which reciprocate coincidentally, may also be actuated by a single eccentric through a similar rock shaft and arms. By this arrangement the eight sleeves will be reciprocated by four eccentrics, each eccentric actuating two sleeves.

As shown particularly in Fig. 6, the rock shaft 53 is arranged in bearings 55 in a separately cast cover 56 which closes the opening 57 in the side of the upper or supporting section 8 of the crank case. This arrangement makes the inspection of the actuating devices convenient and facilitates manufacture.

With the arrangement of sleeves and sleeve actuating means above described, taken at any one time, there are but four positions for the eight sleeves, two sleeves occupying each of these four positions and each position being a quarter period from the next position, which of course makes each position diametrically opposite to one of the other positions. Therefore all eight sleeves may be properly operated from two rock shafts which may be arranged parallel to each other and parallel to the crank shaft and on opposite sides of the cylinder, as shown in Figs. 7 and 8. Here the rock shaft 58 has the opposite arms 59, 60, and the arm 59 is connected by rod 37 with the outer sleeve of cylinder No. 1 and the inner sleeve of cylinder No. 2, and the arm 60 is connected through rod 37 with the inner sleeve of cylinder No. 3 and the outer sleeve of cylinder No. 4, these connections being similar to those of eccentrics 41 and 44 respectively of Fig. 1. The rock shaft 61 is provided with four arms 62, each of which is connected through its respective connecting rod 37 with the inner sleeves of cylinders 1 and 4 and the outer sleeves of cylinders 2 and 3. These connections are shown in Fig. 8 and are similar to those illustrated in Fig. 1, as will be readily understood. The rock shafts 58 and 61 may be rocked by separate eccentrics on a gear driven at half speed

by the crank shaft, the said eccentrics being arranged at an angle of 90° to each other, or the said shafts may be rocked by a single eccentric 63 on a gear 64 meshing with a gear 65 of half its size mounted on the crank shaft 5, this connection being through arms 66 and 67 on the respective rock shafts and connecting rods 68 and 69.

In the particular form shown in Figs. 7 10 and 8 all of the sleeves are not only actuated by the two parallel rock shafts, but those two rock shafts, arranged on opposite sides of the cylinders, are actuated from a single eccentric rotated at half the speed of 15 the crank shaft, and thus all eight sleeves of a four-cylinder motor are actuated from a single eccentric. As above indicated it is desired that the sleeves be actuated a quarter period apart and to this end the 20 rock shafts 58 and 61 are so connected to the eccentric 63 that one of these shafts will be at the middle of its oscillating stroke when the other is at the end of its stroke. As shown the shafts 58 and 61 oscillate about 25 90° and when one is midway of the extremes of its travel the other is at the end of its travel. It will be understood however that the particular angular movement is not essential and those skilled in the art will be 30 able to so arrange and proportion the parts as to secure the desired relative movement and timing. As shown the connecting rods 68 and 69 meet each other at the eccentric 63 at an angle of approximately 90° , and 35 thus when one of these rods is at the end of its reciprocating stroke the other is at the middle of its stroke. For instance, in the position of the arms indicated in Fig. 7 the arm 69 has ceased moving upward and 40 will at once commence to descend, whereas arm 68 is tangent to the path of travel of eccentric 63, and is therefore at the middle of its longitudinal movement. This situation is reversed every time the eccentric 63 45 travels 90° .

An additional feature of the form of the invention illustrated in Fig. 6 is the difference in the velocities of the various sleeves at the different points in their travel. For 50 instance, with the ordinary eccentric movement, the sleeves travel fastest midway of their path of travel, going either up or down, and their speed is slackened toward both ends of their travel. This is of course 55 desirable in this type of motor in order to obtain a quick opening and closing of the inlet and exhaust ports and at the same time to have the sleeves moving slowly during the time that the ports are covered. This 60 difference in movement of the sleeves at the center and at the ends of their travel is augmented by the action of the rock shafts 58, 61 and their short arms, since said arms are at an angle of about 45° at the extremes

of their movement and thus are moving the 65 sleeves slower toward the upper and lower positions than they are at the center of the stroke. Of course all of these movements are relative and as above stated the rock shafts merely augment or intensify the action 70 of the eccentric 63.

With the above explanation it is believed that the operation of the motor and the various forms of valve actuating means will be obvious to those skilled in the art. 75

Nearly all hydrocarbon motors used in motorvehicle construction at the present time are designed to be started by hand, that is, the first turn of the crank shaft is given by the operator to start the motor on 80 its proper cycle of operation. In the larger motors of this character some difficulty is experienced in compressing the charge by thus turning the crank shaft by hand and various devices have heretofore been designed for partially relieving the compression during the compression stroke of the piston. In a four-stroke cycle motor it is of course desirable that the cylinder be open 85 to the atmosphere to relieve the pressure 90 during a part only of the compression stroke of the piston and not during the entire period of this stroke even in cranking, and during all of the other strokes of the piston it should be closed. If a pet cock is employed 95 in the head of the cylinder for the purpose of relieving the compression, this pet cock must also remain open during the intake stroke of the motor and thus considerable air is drawn into the cylinder 100 which rarifies the mixture and increases the difficulty of starting. Moreover, the compression is too much relieved for the reason that the pet cock remains open during the entire compression stroke. The ideal situation 105 therefore is the provision of a separate valve which shall be opened during a part only of the compression stroke of the piston, and in the present invention such a device is embodied, which device will now 110 be described.

Referring particularly to Figs. 1 and 2, it will be noted that the inner sleeve 23 is provided in one side with a port 46 and that the outer sleeve 26 has a similar port 47, and 115 these ports are so arranged that they will overlap or be in register during a part of the compression stroke of the piston. They are shown so in register in Fig. 3. In the side of the cylinder and adapted to register 120 with the ports 46 and 47, when they themselves are in register, is a relief port 48, the outlet of which is controlled by a pet cock 49, and when said pet cock is opened the gas discharged from the same enters the 125 pipe 50 by which it is conveyed to the atmosphere beneath the motor or to any other convenient place.

Fig. 3 shows the piston 13 on its compression stroke before it reaches the port 46. Both sleeves are traveling upwardly as is indicated by their connections with the eccentrics and by the arrows, and as the outer sleeve will from that point travel slightly faster than the inner sleeve, owing to the greater angularity of its connecting rod 37, it will be seen that the ports 46, 47 and 48 will be out of register at about the same moment that the piston 13 overrides the port 46. Thus the relief port 48 is cut off from the interior of the cylinder until the next compression stroke of the piston, the ports 46 and 47 being out of register on the next up or exhaust stroke of the piston. Of course the pet cock 49 may be operated to close the port 48 at any time and the compression relief is then inoperative.

Having thus described the invention what is claimed is:

1. In a motor, the combination with four cylinders, the pistons therein, and a crank shaft, of a valve mechanism adapted to cause the power strokes of the pistons to occur in succession, said mechanism including a sliding valve for each cylinder, a valve shaft having thereon an eccentrically mounted member, means for rotating said valve shaft from the crank shaft, and connections from said eccentrically mounted member to said valves for operating the latter.

2. In a four cylinder motor, the combination with the cylinders, the pistons therein, the crank shaft, and a pair of sliding valves for each cylinder, of a valve shaft having thereon an eccentrically mounted member, means for rotating said valve shaft from the crank shaft, and connections from said eccentrically mounted member to said valves adapted to cause the power strokes of the pistons to occur in succession.

3. In a four cylinder motor, the combination with the cylinder, the pistons therein, the crank shaft, and a pair of sliding valves for each cylinder provided with coöperating ports adapted to be brought into register, of a valve shaft having thereon an eccentrically mounted member, means for rotating said valve shaft from the crank shaft, and connections from said eccentrically mounted member to said valves adapted to cause the power strokes of the pistons to occur in succession.

4. In a multi-cylinder motor, the combination with the cylinders, the pistons therein, and a crank shaft, valve mechanism including a sliding valve for each cylinder, a valve shaft having thereon an eccentrically mounted member, means for rotating said valve shaft from the crank shaft, and connections from said eccentrically mounted member to said valves adapted to cause the

power strokes of the pistons to occur in 65 succession.

5. In a multi-cylinder motor, the combination with the cylinders the pistons therein, the crank shaft, and a pair of sliding valves for each cylinder, of a valve shaft 70 having thereon an eccentrically mounted member, means for rotating said valve shaft from the crank shaft, and connections from said eccentrically mounted member to said valves adapted to cause the power strokes of 75 the pistons to occur in succession.

6. In a multi-cylinder motor, the combination with the cylinders, the pistons therein, the crank shaft, and a pair of sliding valves for each cylinder provided with operating ports adapted to be brought into 80 register, of a valve shaft having thereon an eccentrically mounted member, means for rotating said valve shaft from the crank shaft, and connections from said eccentrically mounted member to said valves adapted to cause the power strokes of the pistons to occur in succession.

7. In a four cylinder motor, the combination with the cylinders, the pistons therein, 90 the crank shaft, and a pair of sliding valves for each cylinder, of a valve shaft having thereon an eccentrically mounted member, means for rotating said valve shaft from the crank shaft, connections from said eccentrically mounted member to four of said 95 valves for operating the same, and means for operating the remaining valves.

8. In a four-cylinder motor, the combination with the cylinders, the pistons therein, 100 and a pair of sliding valves for each cylinder, of a rock shaft connected to reciprocate four of said valves, means for rocking said rock shaft, and means for reciprocating the other four valves.

9. In a four cylinder motor, the combination with the cylinders, the pistons therein, and a pair of sliding valves for each cylinder, of two rock shafts connected to operate all of said valves, and means for rocking 110 said rock shafts.

10. In a multi-cylinder motor, the combination with the cylinders, the pistons therein, and a pair of movable valve sleeves surrounding each piston and having coöperating 115 ports of a valve operating shaft driven by the crank shaft, and rock shafts having arms connected respectively with certain of said sleeves and with said valve shaft.

11. In a multi-cylinder motor, the combination with the cylinders, the pistons therein, and a pair of movable valve sleeves surrounding each piston and having coöperating ports of a valve operating shaft driven by the crank shaft, a rock shaft having arms 125 connected respectively with one of said sleeves and with an actuating part of said valve shaft whereby said sleeve is recipro-

- cated, and means for reciprocating the remaining sleeves of said motor.
12. In a multi-cylinder motor, the combination with the cylinders, the pistons therein, and a pair of movable valve sleeves surrounding each piston and having coöperating ports, of a plurality of connecting rods for imparting movement to said sleeves, one of said rods being connected to actuate a plurality of sleeves simultaneously in the same direction.
13. In a multi-cylinder motor, the combination with the cylinders having inlet and exhaust ports, and the pistons in said cylinders, of a pair of valve sleeves surrounding each piston, said sleeves having ports and being movable to coöperate in covering and uncovering the ports in the cylinders, the movement of one sleeve of each pair being in phase with the movement of one of the sleeves of another pair, and means for imparting the required movement to the sleeves.
14. In a multi-cylinder motor, the combination with the pistons, of a pair of valve sleeves surrounding each piston having inlet and exhaust ports adapted to be brought into register, means for connecting said ports with the supply and exhaust respectively when in register, and means for moving one sleeve of each pair in phase with the sleeve of another pair.
15. In a multi-cylinder motor, the combination with the pistons, of a pair of valve sleeves surrounding each piston having inlet and exhaust ports adapted to be brought into register, means for connecting said ports with the supply and exhaust respectively, when in register, and means for moving the inner sleeve of one pair in phase with the outer sleeve of another pair.
16. In a multi-cylinder motor, the combination with the cylinders having inlet and exhaust ports, and the pistons in said cylinders, of a pair of valve sleeves surrounding each piston, said sleeves having ports and being movable to coöperate in covering and uncovering the ports in the cylinders, and means for moving the inner sleeve of each pair in phase with the outer sleeve of another pair.
17. In a multi-cylinder motor, the combination with the cylinders having inlet and exhaust ports, and the pistons in said cylinders, of a pair of valve sleeves surrounding each piston, said sleeves having ports and being movable to coöperate in covering and uncovering the ports in the cylinders, and means for moving the inner sleeve of one pair in phase with the outer sleeve of another pair.
18. In a multi-cylinder motor, the combination with the cylinders having inlet and exhaust ports, and the pistons in said cylinders, of a pair of valve sleeves surrounding each piston, said sleeves having ports and being movable to coöperate in covering and uncovering the ports in the cylinders, connections whereby one sleeve of each pair will partake of and be in phase with the movement of one of the sleeves of another pair, and means for imparting movement to all of the sleeves.
19. In a multi-cylinder motor, the combination with the cylinders having inlet and exhaust ports, and the pistons in said cylinders, of a pair of valve sleeves surrounding each piston, said sleeves having ports and being movable to cover and uncover the ports in the cylinders, the movement of one sleeve of each pair being in phase with the movement of one of the sleeves of another pair, and means for imparting the required movement to the sleeves.
20. In a multi-cylinder motor, the combination with the pistons, of a pair of valve sleeves surrounding each piston said sleeves having ports and being movable to bring the ports into register the movement of one sleeve of each pair being in phase with the movement of one of the sleeves of another pair, and means for imparting the required movement to the sleeves.
21. In a multi-cylinder motor, the combination with the pistons, of a pair of longitudinally sliding valve sleeves surrounding each piston, said sleeves having ports adapted to be brought into register, and means for moving one sleeve of each pair in phase with one of the sleeves of another pair.
22. In a multi-cylinder motor, the combination with the cylinders having inlet and exhaust ports and pistons in said cylinders, of a pair of valve sleeves for each piston said sleeves being movable to cover and uncover the ports in the cylinders, and means for moving one sleeve of each pair in phase with one sleeve of another pair.
23. In a four-stroke cycle hydrocarbon motor, a cylinder having inlet and exhaust ports and a relief port, and means common to all of said ports for opening and closing the inlet and exhaust ports and for opening the relief port during the compression stroke only.
24. In a four-stroke cycle hydrocarbon motor, a cylinder having inlet and exhaust ports arranged on opposite sides thereof and a relief port, and positively actuated valves for opening and closing the inlet and exhaust ports and for opening the relief port during the compression stroke only.
25. In a four-cycle hydrocarbon motor, the combination with the cylinder and piston working therein, said cylinder having a relief port in its wall approximately midway of the travel of the piston whereby said port is uncovered by said piston during ap-

- proximately half of its stroke, means operated by the motor for closing said port during the down strokes and one of the up-strokes of the piston, and manually operable means controlling said port. 65
26. In a four-cycle hydrocarbon motor, the combination with the cylinder and piston working therein, said cylinder having a relief port in its wall approximately midway of the travel of the piston whereby said port is uncovered by said piston during approximately half of its stroke, means operated by the crank shaft for closing said port during both down strokes and during one 70 and part of the other upstroke of the piston, and manually operable means controlling said port. 75
27. In a four-cycle hydrocarbon motor, the combination with the cylinder, the piston working therein, and a pair of valve sleeves surrounding the piston and adapted to slide one within the other between the piston and the cylinder walls, said cylinder having a relief port in its wall approximately midway of the travel of the piston and said sleeves having ports which coöperate to open and close the cylinder relief port to the combustion chamber of the motor, and means for reciprocating said sleeves to open 80 said relief port during a part of the compression stroke only of the piston, of a manually operable valve for controlling the outlet of said relief port. 85
28. In a four-cycle hydrocarbon motor, the combination with the cylinder, the piston working therein, and a pair of valve sleeves surrounding the piston and adapted to slide one within the other between the piston and the cylinder walls, said cylinder having a relief port in its wall and said sleeves having ports which coöperate to open and close the cylinder relief port, and means for reciprocating said sleeves to open said relief port during a part of the compression stroke only 90 of the piston, of a manually operable valve for controlling the outlet of said relief port. 95
29. In a multiple cylinder motor, the combination with a plurality of cylinders, pistons therein, a crank shaft, and valve mechanism including a sliding valve for each cylinder, of a shaft having thereon an eccentrically mounted member, and means connecting said member with a plurality of said valves and adapted to cause the power strokes of the pistons to occur in succession. 100
30. In a multiple cylinder motor, the combination with a plurality of cylinders, pistons therein, a crank shaft, and a plurality of sliding valves for each cylinder, of a shaft having thereon an eccentrically mounted member, and means connecting said valves with said member and adapted to cause the power strokes of the pistons to occur in succession. 105
31. In a multiple cylinder motor, the combination with a plurality of cylinders, pistons therein, a crank shaft, and a plurality of sliding valves for each cylinder, of a shaft having thereon an eccentrically mounted member, and means connecting said member with a plurality of said valves and adapted to cause the power strokes of the pistons in said cylinders to occur in succession. 115
32. In a multi-cylinder motor, the combination with a plurality of cylinders, pistons therein, a crank shaft, and valve mechanism including a sliding valve for each cylinder, one of the valves for each cylinder leading the other, and an eccentric connected to operate the leading valve of one cylinder and the lagging valve of another cylinder. 120
33. In a multi-cylinder motor, the combination with a plurality of cylinders, pistons therein, a crank shaft, and a plurality of sliding valves for each cylinder, of a rock shaft connected to reciprocate a plurality of said valves, and means for reciprocating the other valves. 125
34. In a multi-cylinder motor, the combination with a plurality of cylinders, pistons therein, a crank shaft, and a plurality of sliding valves for each cylinder, of a pair of rock shafts for reciprocating all of said valves. 130
35. In a motor, the combination of the cylinder and piston therein, said cylinder having inlet and exhaust ports and a relief port, means for closing and opening said inlet and exhaust ports to operate the motor on the desired cycle, and positively operated means for closing said relief port and opening it to the cylinder during a part of one stroke only of the motor. 135
36. In a motor, the combination of the cylinder and piston therein, said cylinder having inlet and exhaust ports and a relief port, means for closing and opening said inlet and exhaust ports to operate the motor on the desired cycle, and means operated by the piston for uncovering said relief port during a part only of the stroke of the motor. 140
37. In a hydrocarbon motor, the combination of the cylinder and piston working therein, said cylinder having inlet and exhaust ports and a relief port, means for closing and opening said inlet and exhaust ports to operate the motor on the four-stroke cycle, and means for closing said relief port and opening it to the cylinder during the early part of the compression stroke only. 145
38. In a hydrocarbon motor, the combination of the cylinder and piston working therein, said cylinder having inlet and exhaust ports and a relief port, means for closing and opening said inlet and exhaust ports to operate the motor on the four-stroke cycle, 150

and means for closing said relief port and opening it to the cylinder during the early part of the compression stroke only, and a manually operable valve for controlling the outlet of said relief port.

39. In a four-stroke cycle hydrocarbon motor, the combination of the cylinder and piston, said cylinder having inlet and exhaust ports and a relief port, of means movable within the cylinder for opening and closing

said inlet and exhaust ports and for opening the port during the compression stroke and for maintaining the relief port closed during the remaining strokes of the cycle.

In testimony whereof I affix my signature 15
in presence of two witnesses.

ALLEN LOOMIS.

I. HARDING,
C. I. DALE.

Copies of this patent may be obtained for five cents each, by addressing the "Commissioner of Patents,
Washington, D. C."

It is hereby certified that in Letters Patent No. 1,163,935, granted December 14, 1915, upon the application of Allen Loomis, of Detroit, Michigan, for an improvement in "Hydrocarbon-Motors," errors appear in the printed specification requiring correction as follows: Page 2, line 9, for the word "befere" read *before*; page 8, line 12, claim 39, before the word "port" insert *relief*; and that the said Letters Patent should be read with these corrections therein that the same may conform to the record of the case in the Patent Office.

Signed and sealed this 11th day of January, A. D., 1916.

[SEAL.]

J. T. NEWTON,

Acting Commissioner of Patents.

Cl. 123—59.
